(57) **CLAIM**

We claim the ornamental design for an automotive vehicle front door, as shown and described.

DESCRIPTION

FIG. 1 is a perspective view of an automotive vehicle front door, of the new design;

FIG. 2 is a front view thereof;

FIG. 3 is a top view thereof;

FIG. 4 is an end view thereof;

FIG. 5 is an end view thereof, opposite that of FIG. 4;

FIG. 6 is a bottom view thereof; and,

FIG. 7 is a back view thereof.

The stippled portions indicate a darker color than the unstippled portions at and above the arm rest area. The broken and dotted lines in FIG. 7 indicate portions internal thereto which form no part of the claimed design. The broken and dashed lines are for environmental illustrative purposes only and form no part of the claimed design.
